UNITED STATES PATENT OFFICE.

EDWARD O. SCRIVEN, OF NEW YORK, N. Y., ASSIGNOR TO WESTERN ELECTRIC COMPANY, INCORPORATED, OF NEW YORK, N. Y., A CORPORATION OF NEW YORK.

ALTERNATING-CURRENT SOURCE.

Application filed July 16, 1918. Serial No. 245,140.

To all whom it may concern:

Be it known that I, EDWARD O. SCRIVEN, a citizen of the United States, residing at New York, in the county of New York, 5 State of New York, have invented certain new and useful Improvements in Alternating-Current Sources, of which the following is a full, clear, concise, and exact description.

10 This invention relates to alternating current sources of the electron discharge type.

More particularly this invention relates to oscillators of the electron discharge type, in which the frequency of the oscillations 15 generated is governed by a tuned oscillation circuit, the natural frequency of which may be varied.

An object of the invention is to provide 20 an oscillator which will generate substantially pure sine waves.

Another object of the invention is to provide an oscillator of the electron discharge type having coupled output and input circuits, with means for preventing harmonic 25 frequency oscillations from being fed back to the input circuit.

A further object of the invention is to provide means for varying the tuning of the frequency governing circuit of an electron 30 discharge oscillator without materially varying the feed-back coupling.

A still further object is to provide an oscillator having a frequency governing circuit in which the natural period may be varied by changing either the capacity or the inductance of the circuit.

Still other objects and advantages of the invention will appear from the following detailed description, taken in connection 40 with the drawing, in which Fig. 1 represents diagrammatically the circuit arrangements of an oscillator; and Fig. 2 illustrates a modification of the tuned circuit of Fig. 1.

Referring to the drawing, an evacuated 45 electron relay or discharge device 1 includes a constantly active source 2 of electrons, preferably a hot filament cathode, a plate electrode or anode 3, and a grid or impedance varying element 4. Cathode 2 is 50 maintained electronically active by a source 5 of heating current connected to its terminals through a variable resistance 6 for regulating the temperature of the cathode. The grid-cathode or input circuit includes 55 a coupling or secondary winding 7 and may also include a source 8 for determining the

normal potential of grid 4 with respect to the cathode 2, and in consequence, the normal impedance offered to electron discharge current between electrodes 2 and 3, although 60 this source is not ordinarily necessary.

The output or plate-filament circuit includes a space current branch and a divided path oscillation current branch, this latter branch having a feed-back winding and a 65 frequency determining oscillation circuit in parallel. The space current branch includes a source of space current 9, a choke coil 10, and a variable high resistance 11, the function of which will appear later. The frequency determining oscillation circuit includes a variable capacity 12 and a variable inductance 13, which may be an ordinary 70 variable air core inductance as indicated in Fig. 2, but which for low frequency oscillations, requiring oscillation circuits of large 75 natural period, is preferably wound upon a toroidal magnetic core in order to reduce the size of the element necessary to give the required inductance. In parallel with the oscillation circuit is a winding 14, inductively related to winding 7. In series with winding 14 and the oscillation circuit is a blocking capacity 15, the function of which is to prevent local flow of unidirectional current from source 9 through elements 13 and 14. Conductors 16 and 17 connected to the terminals of winding 7 serve as output connections for the oscillator, element 7 being in effect an autotransformer. Conductors 16 80 and 17 are preferably connected to the load circuit through a high impedance element in order to prevent undesirable reactions on the oscillator through winding 7, which would otherwise vary the frequency of the oscillations generated. Such an impedance element may be a three-electrode vacuum tube 85 amplifier or repeater such as element 18 to the output circuit of which a load circuit 19 is connected. Obviously any other form of 90 high impedance may be employed.

If the closed oscillation circuit 12, 13 be disturbed electrically oscillations will be set up of approximately the natural frequency of the circuit. Without the amplifying effect of the electron discharge device 1, these would soon be damped out. By virtue 105 of transformer 14, 7, these oscillations set up an alternating potential between the input elements 2 and 4 of the discharge device. This alternating potential is of the 110 frequency of the oscillations set up in cir-

cuit 12, 13, and if the winding 7 be coupled in the proper manner to winding 14, it will be of such phase that the change it produces in the space current will reinforce the oscillations in the oscillation circuit. For sustained oscillations, this increased oscillation current must just offset the normal decrease due to the damping of the system. The operational characteristics of the discharge device being a function of the magnitude of the alternating current in it, the latter adjusts itself to meet this condition. In this manner oscillations having a frequency which is determined by the constants of the tuned circuit are set up. The natural frequency of this tuned circuit may be changed by varying the capacity 12 or inductance 13, thus permitting a change in the frequency of the oscillations generated.

20 Choke coil 10 excludes all oscillation current components from the path including the space current source. Circuit 12, 13 is tuned to the desired frequency and offers a substantially infinite impedance to currents 25 of this frequency, which will therefore traverse the path followed by winding 14 and condenser 15. Winding 14 offers high impedance to high frequency currents such as the harmonics usually present in systems of 30 this character, while the branches 12, 13 of the tuned circuit offer a relatively low impedance, thus shunting out these undesired components and preventing feed-back of such frequencies to input winding 7. The 35 electron relay may, in one sense, be considered as a reamplifying device for currents of one frequency only. For this reason the device operates to generate relatively powerful fundamental oscillations with weak harmonics. The wave filter 40 which must ordinarily be provided with oscillators to eliminate harmonics where a pure fundamental frequency current is desired is ordinarily unnecessary with the circuit arrangement just described.

The characteristic curve plotted between space voltage and space current of evacuated electron discharge devices is, in general, non-linear, and accordingly changes in voltage 50 of the source 9 produce larger changes in the space current. Changes of the space current or of the impedance between the output electrodes may cause changes in the frequency of the oscillations generated.

55 Resistance 11 has a substantially linear impedance characteristic and the series impedance of tube 1 and resistance 11 is therefore much more nearly linear than is that of tube 1 alone. In consequence of this stabilizing action of resistance 11 there is little tendency for changes in frequency to occur for the reason that the current furnished by source 9 can vary only slightly.

If it is desired to change the frequency of 60 the oscillations generated, either capacity

12 or inductance 13 or both may be varied without affecting the feed-back coupling or varying the impedance presented to space current in the space current circuit. Since inductance winding 13 is not traversed by 70 unidirectional current, the magnetic core may be operated over a wide range without approaching magnetic saturation.

While the invention has been illustrated and described in connection with a particular form of circuit arrangement it is to be understood that it is not to be limited thereto but only by the scope of the appended claims.

What is claimed is:

1. In an oscillator, an electron discharge device having an input circuit and an output circuit, said output circuit having means to feed back energy oscillations of a given frequency to said input circuit, and additional means for substantially preventing the feeding back of energy oscillations of other frequencies. 80

2. In an oscillator, an electron relay having an input circuit and a output circuit, 90 said output circuit comprising a closed tuned circuit and a high frequency path in shunt to said tuned circuit.

3. In an oscillator, an electron relay having an input circuit and an output circuit, 95 said output circuit comprising a closed tuned circuit, and a high frequency path coupled to said input circuit in shunt to said tuned circuit.

4. In an oscillator, an electron discharge device having an input circuit and a divided output circuit, one branch of which is coupled to said input circuit and another branch of which includes a circuit tuned to the frequency of the oscillations generated. 100

5. An oscillator comprising an electron relay having an input circuit and a divided output circuit, one branch of said output circuit having a lower impedance than the remainder of the divided circuit for currents of the frequency generated by said oscillator and having a higher impedance than the remainder of the divided circuit for currents of other frequencies. 110

6. An oscillator comprising an electron discharge device having an input circuit and an output circuit, said output circuit comprising a closed tuned circuit and a high frequency path in shunt thereto, and means for varying the natural period of said tuned 120 circuit.

7. In a oscillator, an electron discharge device having an input circuit and an output circuit, means coupling said output circuit to said input circuit, and means shunting said coupling means to divert therefrom substantially all currents except those of the frequency generated by said oscillator. 125

8. An electron relay having input and output circuits, means to feed back energy of 130

- oscillation currents of one frequency from said output circuit to said input circuit, whereby said oscillation currents may be amplified, and means to prevent the feed-back of energy of other frequency currents.
9. In an oscillator, an electron discharge device having an impedance varying element, space current electrodes and an output circuit connected to said electrodes comprising a closed tuned circuit and a high frequency path in parallel to said tuned circuit, and means whereby the potential of said impedance varying element is varied in accordance with the current in said output circuit.
10. An oscillator comprising an electron discharge device having a cathode, an anode and an impedance controlling element, an input circuit connected to said cathode and said impedance controlling element and an output circuit connected to said cathode and said anode, said output circuit having means to feed back oscillations of a given frequency to said input circuit, and additional means for substantially preventing the feeding back of energy oscillations of other frequencies.
11. An oscillator comprising an electron discharge device having input and output circuits, said output circuit comprising a plurality of branches, means to exclude variation currents from one branch, means to exclude from a second branch currents of the frequency which are produced by the oscillator, and means coupling a third branch to said input circuit.
12. A discharge device comprising a cathode and an anode and a branched circuit connected to said cathode and anode for generating oscillations, one branch of said circuit including in series a source of electromotive force, a high resistance element, and an element offering high impedance to variable current, a second branch of said circuit including a closed loop tuned to substantially the frequency of the oscillations to be generated, a work circuit, and means in said branched circuit but external to said tuned loop for connecting said branched circuit in energy transfer relation to said work circuit.
13. An oscillator comprising an electron discharge device having input and output circuits, means coupling said circuits, and means comprising an anti-resonant circuit connected in parallel with said coupling means for determining the frequency of the oscillations generated independently of said coupling means.
14. An oscillator comprising an electron discharge device having input and output circuits, a transformer for coupling said circuits, and means comprising an anti-resonant circuit connected in parallel with a winding of said transformer for determin-
- ing the frequency of the oscillations generated independently of said transformer winding.
15. An oscillator comprising an electron discharge device having input and output circuits, a parallel tuned circuit associated therewith for determining the frequency of the oscillations generated, and means connected in parallel to said tuned circuit for coupling said input circuit with said output circuit.
16. In an oscillator, an electron discharge device having an input circuit and a divided output circuit one branch of which is coupled to said input circuit and another branch of which includes a closed circuit tuned to the frequency of the oscillations generated.
17. In an oscillator, an electron discharge device having a cathode, an anode, and an impedance controlling element, an input circuit connecting said cathode and impedance controlling element, a divided cathode anode circuit having two parallel portions, one of said portions being coupled to said input circuit, and the other of said portions being tuned to substantially independently determine the frequency of the oscillations generated.
18. In an oscillator, an electron relay having an input circuit and an output circuit, said output circuit comprising an anti-resonant circuit, a high frequency path in shunt to said anti-resonant circuit, and another path in shunt to said anti-resonant circuit including in series a source of electromotive force, a high resistance element and an element offering high impedance to variable current.
19. An oscillator comprising an electron discharge device having input and output circuits, said output circuit comprising a plurality of branches, means to exclude variation currents from one branch, means to exclude from a second branch currents of the frequency which are produced by the oscillator, means coupling a third branch to said input circuit, and a high resistance element connected in series with said first mentioned branch only.
20. A discharge device comprising a cathode and an anode, a branched circuit connected to said anode and cathode, one branch of said circuit including in series a source of electromotive force, a high resistance element, and an element offering high impedance to variable current, a second branch of said circuit including a closed tuned loop, a work circuit, and means in a third branch of said branched circuit for connecting said branched circuit to said work circuit.
- In witness whereof, I hereunto subscribe my name this 8th day of July, A. D., 1918.
- EDWARD O. SCRIVEN.
